UNITED STATES PATENT OFFICE.

JOHN IRELAND BOOKER, OF LIVERPOOL, COUNTY OF LANCASTER,
ENGLAND.

GRAIN CLEANING AND WASHING APPARATUS.

SPECIFICATION forming part of Letters Patent No. 369,768, dated September 13, 1887.

Application filed January 5, 1887. Serial No. 233,478. (No model.) Patented in England June 19, 1886, No. 8,158.

To all whom it may concern:

Be it known that I, JOHN IRELAND BOOKER, a subject of the Queen of Great Britain, residing at Liverpool, in the county of Lancaster, in the Kingdom of Great Britain, have invented certain new and useful Improvements in Grain Cleaning and Washing Apparatus, (for which provisional protection has been obtained in England, dated June 19, 1886, No. 8,158,) of which the following is a specification.

This invention relates to certain improvements in machines for cleaning or washing grain or other seed, and is designed to prevent the casing from being choked up, to insure the better washing of the wheat, to enable the wire covering to be easily cleaned, and to increase the efficiency of the rinsing of the grain.

Referring to the drawings annexed hereto, Figure 1, is a sectional elevation of my improved machine. Fig. 2 is a plan with top removed. Fig. 3 is an end elevation.

In the drawings, A is the driving-shaft revolving in suitable bearings, *a*, which are fitted in brackets attached to the tank B and provided with a driving-pulley, *a*². This tank is constructed to hold a supply of water and is fitted with a valve, *b*, to draw off the water when required.

C is a wire casing or cylinder partially submerged in the water contained in the tank B. The two halves of the casing may be fastened together at the center by any suitable means, so that one half may be easily removable for the purpose of cleaning the inside or of repairing or removing the worm *c*¹ or beaters *c*², hereinafter described. Although I prefer to make the casing in two halves, I do not limit the invention thereto.

The casing is constructed to revolve independently of the shaft A, and is furnished with suitable bearings, *b*¹, formed in the tank B. The casing is fitted with wheels D, which gear with the wheel D¹, fixed on the shaft E. This shaft 45 may be driven by the belt-pulleys F F. On the same shaft, E, is fitted a brush, E¹, which brushes against the surface of the wire casing C and prevents the casing being choked. On the surface of the shaft A, inside the wire cylinder C, I form a worm, *c*¹, the blades of which 50 may be extended, so as to form paddles or

beaters *c*², or a continuous screw-thread may be used, if preferred, and on the ends of the shaft A the worm is extended to form the feed and exit worms *c*³ *c*⁴. They may either be 55 fixed to the same shaft as the main worm or on sleeves revolving on the same independently. The water for washing purposes is preferably forced in by an injector, H, through a central channel in the main shaft A and out 60 through perforations in the same, as shown at *h*, near the exit end or conical part of the casing. The height of the water in the wire casing C may be regulated from one and one-half to eight inches. In the old machines the height 65 can only be regulated from one to two inches. The whole machine may be fixed on suitable frames, L.

The action of my machine is as follows: The grain is fed into the machine through the hopper K by means of the feed-worm *c*³. As the beaters *c*² revolve at a different speed from the wire casing C, the grain is thoroughly stirred up and washed in the hot water supplied by the injector H. The action of the beaters will 70 be also to feed the grain toward the conical end of the wire casing C, which is not submerged in water. It now comes in contact with the fresh warm water flowing through the jets *h*. As it rises still higher, it is drained by 75 means of perforations into a vessel or rinsing-box, M, from whence the drainings are carried away by the pipe *m*, and finally is drawn out of the machine by the exit-worm *c*⁴ through the exit-spout N. The whole process is 80 continuous.

Having now particularly described and ascertained the nature of the said invention, and in what manner the same is to be performed, I declare that what I claim is—

1. In a machine of the class described, the combination, with a tank adapted to contain water, of a shaft extending longitudinally through the same, an approximately horizontal perforate casing also mounted within the tank, mechanism for imparting motion in opposite directions to the casing and shaft, respectively, and beaters secured to the shaft, all substantially as shown.

2. In a machine of the class described, the combination, with a tank adapted to contain water, of a hollow shaft extending longi-

tudinally through the same and provided with a water-supply pipe, a perforate casing also mounted within the tank, mechanism for imparting motion to the casing and to the shaft, 5 and beaters secured to the shaft, all substantially as shown.

3. In combination with tank B, provided with hopper K and discharge-spout N, a shaft, A, provided with worms c^1 c^2 and beaters c^3 , a 10 perforate casing, C, surrounding the shaft and mounted within the tank, and mechanism, substantially such as shown, for imparting rotary motion to the shaft and to the perforate casing.

4. In combination with tank B, having hopper K and spout N, a perforate casing, C, provided with a gear-wheel, D, a shaft, E, provided with a gear, D', to mesh with gear D, shaft A, provided with beaters and located 15 within the perforate casing, a band-wheel mounted on shaft A, and a belt for transmitting motion from shaft A to shaft E.

5. In combination with a tank, B, and a

perforate casing mounted and adapted to rotate therein, a hollow shaft mounted within the perforate casing, provided with lateral outlets h and with beaters c^2 , arranged spirally about the shaft, a worm at each end of the shaft, and mechanism for imparting motion in opposite directions to the shaft and the casing. 25

6. In combination with tank B and a rotatable perforate casing C, mounted therein, a hollow shaft provided with beaters and worms and adapted to be rotated in a direction reverse to that of the casing, and a brush arranged, substantially as shown and described, 30 to rotate in contact with the casing.

In testimony whereof I have signed my name to this specification in the presence of two subscribing witnesses.

JOHN IRELAND BOOKER.
